ALBIN F. GOETZE, OF NEWARK, NEW JERSEY, ASSIGNOR TO MORGAN KNITTING MILLS, INC., OF NEWARK, NEW JERSEY, A CORPORATION OF NEW JERSEY.

KNIT SCARF.

Application filed January 18, 1927. Serial No. 161,872.

This invention relates to knit garments and particularly to a knit scarf, the object being to provide a knit structure wherein there is a loosely knit center and a tightly knit edge.

A further object of the invention is to provide a knit article wherein there is provided a tightly knit edge at the sides and ends and loose knitting in the center imitating hand knitting in appearance and presenting a very distensible structure.

In the accompanying drawing—

Figure 1 is a plan view of a knit scarf disclosing an embodiment of the invention.

Figure 2 is an enlarged fragmentary view of part of the scarf shown in Figure 1.

Figure 3 is an enlarged view of part of the center of the scarf shown in Figure 1, illustrating the scalloped or festooned arrangement of loops.

Referring to the accompanying drawing by numerals, 1 indicates the body of the garment which is provided with a loosely knit structure, the loops of which fall over giving to the body a festooned formation. The knit body 1 merges into side edges 2 and 3 and also into the end structures 4 and 5. These end structures and side edges are a tightly or closely knitted section of the garment but formed from the same yarns as the body 1. Where the device is made into a scarf, suitable tassel members

6 and 7 are formed from certain of the yarns. Where the device is to form part of a sweater or to be made up in some other form of garment, the edges 2 and 3 will act to receive the lines of stitching of thread connecting up the parts of the garment. These edges being tight will readily receive lines of stitching very much on the order of woven goods while body 1 is loose in its general appearance. When the parts are stretched appreciably, the body 1 will appear as shown in Figure 2 and the various loops 8 will assume the usual position of an ordinary knit garment. When relaxed, the loops 8 will fall over somewhat and present a festooned structure shown more or less in Figure 3.

The scarf described herein, may be manufactured by the machine and method disclosed in my co-pending application, Serial No. 188,758.

What I claim is:

A machine knit scarf, comprising a flat knitted body having a loosely knit center, the loops of which fall over giving to the loops of the center a festooned formation, and having tightly knit edges and ends, said edges and ends normally maintaining said loops of the center in festooned formation, whereby the scarf presents the appearance of being hand knit.
